ATTORNEYS:

UNITED STATES PATENT OFFICE.

THEODORE W. FOSTER, OF PROVIDENCE, RHODE ISLAND.

DESIGN FOR A COVER FOR TOILET-BOXES OR SIMILAR ARTICLES.

SPECIFICATION forming part of Design No. 34,954, dated August 20, 1901.

Application filed July 19, 1901. Serial No. 68,981. Term of patent 7 years.

To all whom it may concern:

Be it known that I, THEODORE W. FOSTER, a citizen of the United States, residing at Providence, in the county of Providence and 5 State of Rhode Island, have invented and produced a new and original Design for the Covers of Toilet-Boxes or Similar Articles, of which the following is a specification, reference being had to the accompanying drawings, forming part thereof.

Figure 1 is a plan view of a circular cover, showing my new design. Fig. 2 is a transverse section of the same, taken on the line $x x$ of Fig. 1.

15 As shown in the drawings, the leading and material feature of my design consists of the raised representation of a female head, with flowing hair extending from the marginal ornate- 20 nizations, representing in relief four conventional representations of flowers having

radially-extending scrolled leaves connected by stems and scrolled leaves to form a wreath inclosing a central convex panel on which two groups of birds are represented. The floral border presents the conventional appearance of scrolled and twisted cactus leaves and flowers.

Having thus described my invention, what I claim as new, and desire to secure by Letters Patent, is—

25 The design for the cover of toilet-boxes or similar articles, as herein shown and described.

30 In testimony whereof I have signed my name to this specification in the presence of 35 two subscribing witnesses.

THEODORE W. FOSTER.

Witnesses:

B. M. SIMMS,
JOSEPH A. MILLER.
